UNITED STATES PATENT OFFICE

THEODORE GENSMER, OF PORTLAND, OREGON

BOOKREST

Application filed February 28, 1928. Serial No. 257,600.

- The device in preferred form consists in a body element having a foot form at its lower extremity and having an adjusting leg disposed at its back for maintaining the body element in a reclining position upon which the object to be supported is maintained, means being provided for maintaining the object in placed position thereupon and in an open position.
- 10 The primary purpose and object of my invention consists in providing a simple and efficient device for maintaining a book in an inclined position and in opened condition while the same is being perused by the user.
- 15 A further object of my invention consists in providing means adapted not only for use on books, but equally usable for manuscripts, note books and the like.

With these and incidental objects in view, 20 the invention consists in certain novel features of construction and combination of parts, the essential elements of which are set forth in the appended claim, and a preferred form of embodiment of which is hereinafter 25 shown with reference to the drawings which accompany and form a part of this specification.

In the drawings:—

Fig. 1 is a front, plan view of the device 30 having a book disposed thereupon.

Fig. 2 is a side elevation of the mechanism, illustrated in Fig. 1.

Fig. 3 is a perspective, front, view of the 35 assembled device in preferred embodiment.

Fig. 4 is a perspective view, in preferred embodiment of one of my new and improved devices in a slightly modified form, illustrated in position thereupon, a spring clip for manuscripts adapted for maintaining 40 papers or manuscripts fixedly positioned upon the inclined body element.

Fig. 5 is a side view of the mechanism illustrated in Fig. 4.

Fig. 6 is a fragmentary, rear, view, taken 45 on line 6—6 of Fig. 5, looking in the direction indicated.

Fig. 7 is a side view of the spring clip in preferred embodiment.

Fig. 8 is a perspective view of still a fur- 50 ther preferred embodiment of my device,

illustrating extensible means associated with the body element for handling documents, papers and the like of more than ordinary length or width.

Fig. 9 is a front view, of the mechanism 55 illustrated in Fig. 8, illustrating a book in open position disposed thereupon.

Fig. 10 is a side view of the mechanism illustrated in Fig. 9.

Fig. 11 is a side view of the mechanism 60 illustrated in Fig. 8, illustrating the same in an extended condition.

Fig. 12 is a front view of the mechanism illustrated in Fig. 11.

Fig. 13 is a rear view, taken on line 13—13 65 of Fig. 10, looking in the direction indicated.

Like reference characters refer to like parts throughout the several views.

In preferred embodiment, I form my de- 70 vice, as illustrated in Figs. 1 and 2, wherein I form the body element 1, of sheet material and have upwardly inclined end terminals 2 and 3. An upwardly extending leg 4, is disposed at the rear of the device, against which the book back may be made to engage. 75 I also form upwardly extending clamping bars 5 and 6 against which the clamp 7 may be relatively locked. The clamp 7 has two inwardly extending terminals 8 and 9 which are formed at an obtuse angle to the side 80 walls 10 and 11, so that as the clamp 7 is positioned the ends 8 and 9 will engage the body element 1 and will stress the ends thus maintaining the clamp 7 in a relatively 85 locked position against the object to be supported, irrespective of the position of the same. The cross bar 12 engages the leaves of the book and maintains the same in open, placed position. An upstanding book support 13 is disposed at or near the rear of the 90 body element 1, which is also formed prefer- 95 ably of round spring material having side walls 14 and 15, and having a cross bar 16 connecting the same upon which the book to be supported rests. Inwardly extending 95 ends 17 and 18 engage beneath the clamping bars 19 and 20, the same being formed at an obtuse angle to the side walls of the same, stresses the same when raised to a substantial vertical position, as illustrated in Fig. 1, and 100

maintains the same in placed position. Off-
sets 21 and 22 rest directly upon the body ele-
ment 1, and maintains the upstanding book
support in substantially right angle position
5 to that of the body element 1. When the de-
vice is made, as illustrated in Fig. 1, Fig. 2
and Fig. 3, the two elements disposed at
either end of the body element 1, may be
folded down on the body element and occupy
10 a minimum space for packaging and ship-
ment. A slightly modified form may be
made, as illustrated in Fig. 4 and Fig. 5
wherein the book support 23 disposed upon
the lower forward end of the body element 1,
15 may be made to support the clamping ele-
ment 24. Inwardly extending ends being
made to engage the clamping bars, as hereto-
fore described, and maintaining the same in
engagement with the book to be supported
20 thereupon. When made in this form the
book is made to rest directly upon the body
element 1, and the supporting leg 25 is made
to downwardly extend from the body ele-
ment 1, and rest upon the table or other sup-
25 porting medium. This form of construc-
tion is particularly adapted for the support-
ing of note books, papers, documents and the
like, as illustrated in 26 and wherein a clamp-
ing element 27 may be made to engage the
30 paper or manuscript and support the same.
The same is preferably made of spring ma-
terial, as illustrated in Fig. 7 and wherein
the straight bar 28 may be made to engage the
paper to be supported and a curved terminal
35 29 disposed upon the opposite end of the
clamp may be made to engage the rear of the
body element 1. A slightly modified form
of my device may be made, as illustrated in
Figs. 8, 9, 10, 11, 12 and 13, wherein the body
40 element 1 is made of sheet material and
wherein the lower foot engaging member 30
is slidably disposed, the side walls of the
body element 1, so that the same may be ex-
tended downward for a substantial distance,
45 the book, or paper, or manuscript being held
in position through the medium of the cross
bar 31. Where the papers or documents or
other material to be held are substantially
long, an extensible element 32 may be dis-
50 posed the upper end of the body element and
slidably disposed therein. The leg support
33 being downward extending from the up-
per portion of the body element and engage
between the locking clamps 34 and 35 in the
55 manner heretofore described. If the mate-
rial to be supported is relatively wide, ex-
tensible elements 36 and 37 may be disposed at
the side or sides and be made to slide rela-
tively to the body element beneath the clamps
60 38 and 39, 40 and 41 formed from the body
element 1. If the papers or documents or
other materials are to be held relatively fixed
upon the body element 1, the same may be
held by the clamping device 27, illustrated in
65 Fig. 4 and in Fig. 7.

While the form of mechanism herein shown
and described is admirably adapted to fulfill
the objects primarily stated, it is to be under-
stood that it is not intended to confine the in-
vention to the one form of embodiment here-
in shown, and described, as it is susceptible
70 of embodiment in various forms, all coming
within the scope of the claim which follows:

What I claim is:—

A book rest comprising a one-piece body
element having one of its ends turned in-
wardly to form a ledge, openings disposed on
the oppositely disposed edges of the body
element in spaced relation, a clamping ele-
ment movably associated with the ledge com-
prising a resilient member having an inward-
ly turned back, and downwardly turned
80 arms having inwardly turned terminals
adapted to fit the openings disposed
within the ledge, said terminals being so
shaped as to create a tension between
the back of the resilient member and the body
element, and a U-shaped resilient member
having upturned arms and inwardly turned
90 terminals, said terminals being disposed
within the openings disposed within the body
member and being so constructed as to create
a tension between the resilient member and
the body member, substantially as shown and
described.

THEODORE GENSMER.
